SLIT TYPE STORAGE CHAMBER

Joseph Buschmann, Essen-West, Germany, assignor, by mesne assignments, to Koppers Company, Inc., Pittsburgh, Pa., a corporation of Delaware

Application April 5, 1954, Serial No. 421,128

5 Claims. (Cl. 222—136)

The invention relates to a slit type storage chamber with a central saddle and bearing surfaces for stored material on either side thereof, which material is delivered through one or both of a pair of slits arranged one on each side of the saddle between the same and the bearing surfaces by means of oppositely acting pairs of pivotal diagonal evacuating arms arranged on a carriage in position for engaging upon the two bearing surfaces.

By means of a slit type storage chamber arrangement of this type, different types of material stored in two compartments on opposite sides of the central saddle can be delivered from each compartment in adjustable quantities in order to obtain a predetermined mixture ratio.

In the prior slit type storage chamber of the common assignee's copending Heinz Brahmsiepe application Serial No. 412,526, filed February 25, 1954, the quantity of material to be delivered by the evacuating arms, which act as scrapers or plows, is regulated by means of adjusting members for the arms, and the change of position of the two pairs of evacuating arms on the carriage is effected by diagonal surfaces which are disposed on the storage chamber ends and against which the rearward extensions of the evacuating arms slide. In this case, when the evacuating arms change from the inoperative to the operative position, it is necessary for said arms to travel a distance corresponding to their fully outward pivoted diagonal distance. However, due to the resistance of the material to the evacuating arms, only a gradual outward pivoting of the evacuating arms takes place during their change into the operative position, so that prior to the completion of their outward pivoting, when the material is engaged, the total quantity of material intended to be delivered by them is not delivered at the ends of the storage chamber.

The present invention continues and improves said common assignee's Brahmsiepe system by providing locking hooks which are located near the rearward extension of the evacuating arms and which are under spring tension to maintain the evacuating arms in the inoperative position and which are automatically tripped in the end position of the bunker to release the arms for movement to operative position under the action of a tension spring which adjusts itself to various operative positions of the evacuating arms.

In this way, an immediate release of the said arms, which are locked by the locking hooks, is obtained as soon as the said arms have reached the end of the storage chamber or bunker, and preferably outside the region thereof, so that the arms can immediately be fully opened before engaging in the material, without having first to travel idly over a long path of the material, before becoming fully open, and the complete quantity of material intended to be delivered is thereby delivered at the beginning of the new working movement.

Moreover, in accordance with the invention, the rearward extension of each evacuating arm or plow or scraper is arranged on an angle with the associated evacuating arm so that the extensions of the evacuating arms, when in their operative position, can slide over diagonal

2

surfaces of said Brahmsiepe application, which diagonal surfaces are disposed at the ends of the chamber to engage the locking hooks while the locking hooks are subjected to spring tension to pivot them inwards, thus causing the evacuating arms to move from the operative into, and be held in, the inoperative position, while the locking hooks of the evacuating arms of the other pair which are in the inoperative position abut stops disposed outside the storage chamber, to release their extensions so that the evacuating arms of the other pair move by spring tension from inoperative into the operative position.

A further feature of the invention consists in so disposing the diagonal surfaces of said Brahmsiepe application at the end of the chamber or bunkers that they can be outwardly pivoted to one side, in order that, when the evacuating carriage makes its return movement, the inoperatively positioned evacuating arms can move the diagonal surfaces out of the way by thrusting the same aside.

20 In order to be able to adjust the mixture ratio of the quantity of material to be delivered, regulating or adjusting members are arranged according to the invention in the area of the pivotal movement of the evacuating arms, or of their rearward extensions, said adjusting members also enabling one of the two evacuating arms to be entirely cut out of operation.

A preferred form of the invention is illustrated by way of example in the drawings, wherein:

Figures 1 and 1a illustrate in vertical longitudinal section the lower part of the right and left half, respectively, of a slit-type storage chamber or bunker, according to the invention;

Figures 2 and 2a are horizontal sections along the line II—II of Figures 1 and 1a, respectively;

Figure 3 is a vertical cross-section along the line III—III of Figure 2 on an enlarged scale;

Figure 3a is an enlarged view of a portion of Fig. 3, illustrating the slits 30' and slide members 30 in larger scale;

40 Figure 4 is an enlarged view of part of Figure 2 and illustrates the evacuating arms in their operative position together with the driving arrangement for the arms, and

Figure 5 is an enlarged view of a side elevation of the evacuating arms illustrated in Figure 4.

45 The storage chamber or bunker 1 has in its lower part a saddle 2, above which is disposed a vertical longitudinal wall 25 dividing the bunker into two compartments. The material contained in each compartment rests on a bearing surface 3 and is delivered therefrom by means of the pairs of evacuating arms 5, 6 arranged on a carriage 4. The material is discharged to a conveyor belt 8 through slits 30' and a delivery funnel 7 by means of the arms 5, 6, as they ride along the bearing surfaces 3 when the carriage moves alongside the slits 30'.

The evacuating carriage 4 moves on track 9 by means of running wheels 10. When the pairs of evacuating arms 5, 6 are in their positions as illustrated in Figures 1 and 2, the evacuating carriage is moved to the left along the storage chamber 1 in the direction of the arrow 11 and on movement in the opposite direction to the right, the pairs of arms 5, 6, assume the positions shown in Figures 1a and 2a.

60 The evacuating carriage is driven by means of a motor 31, carried by the carriage 4, which drives an infinitely variable transmission 33 via a bevel drive 32. A chain drive 34 on the shaft of the infinitely variable transmission 33, is connected to the shaft 35 which drives, via gear wheels 36 at each end of the shaft 35, the running wheels 10 for carriage 4.

65 The evacuating arms 5, 6 are mounted in link pins 12

to pivot on the evacuating carriage. As is more particularly apparent from Figure 4, arms 13 are fixed to the link pin 12 for the evacuating arms 5, 6, and engaging in said arms 13 is a spring 14 which is connected to the evacuating carriage at 38 to draw the evacuating arms into their operative position. The evacuating arms 5, 6 have rearward extensions 15, the ends of which are provided with upwardly projecting pins 16 having rollers 26. When the evacuating arms are in their inoperative position, the said vertical pins 16 lie close to locking hooks 17 which so hold the pins 16 that the evacuating arms are maintained in the inoperative position against the return action of the spring 14, as can be seen from the position of the evacuating arms 5 and 6 in Fig. 2a and Fig. 2, respectively. The locking hooks 17 have arms 18, under tension of a spring 19 which is secured to the evacuating carriage 4 at 39. The spring 19 maintains the locking hooks 17 in firm engagement with the pins 16 of the evacuating arms 5, 6, when they are in the inoperative position. When the evacuating arms are in the operative position, the locking hooks 17 bear against a stop 20.

Disposed at each of the opposite ends of the storage chamber 1 are the aforesaid Brahmsiepe diagonally extending sheet metal deflectors 21 which are suspended on a hinge 22 and can therefore be outwardly pivoted to one side. The pins 16 with the rollers 26 of the evacuating arms, when in the inoperative position, are moved past the said deflectors 21 substantially without touching the outermost projecting ends of the deflectors 21. Contrary thereto, the rollers 26 of the evacuating arms, when in the operative position, ride on the deflectors 21 and thereby move the evacuating arms 5, 6, out of their operative into their inoperative position. During this operation, the pins 16 come near the locking hooks 17 which, due to the pins 16 sliding over the diagonal surface 28 of locking hooks 17, are pivoted outwards to some extent and then, as a result of the tension of spring 19, surround the pins 16.

In Figure 2a, the position of arms 5 and 6 is shown when the evacuating carriage 4 has moved from its position shown in Fig. 2 to the extreme left sufficiently for the surface 23 of arm 41 to release pins 16 of arms 5 from their hooks 17, this movement causing the evacuating arms 5 to change to their operative position. From Fig. 2a it will also be apparent that the pins 16 bearing the rollers 26 (Figs. 3 to 5) which are associated with the evacuating arms 6 are at this time restrained by their locking hooks 17 to hold the evacuating arms in their inoperative position, for operation in evacuation during movement of the carriage towards the right hand side of Figs. 2a and 2.

This reversal takes place at each end of Figs. 1 and 1a, at the instant at which the rollers 26 of the evacuating arms 5, 6 move away from the wider region of the deflectors 21, the inoperative arms being released to operative position when rollers 29 disposed on the arms 18 of the locking hooks 17 of the evacuating arms 5 abut the inclined surface 23 of a projecting arm 41 arranged on a fixed wall as at 40. The members 41 (Figure 1) engage 29 to pivot hook 17 against spring 19 to release pin 16 from the terminal part 28 of hook 17, so that spring 14 can act to rotate arms 5, 6, to their operative position. This moves the locking hooks 17 out of the way of the pins 16, whereby the evacuating arms 5, 6 immediately assume their operative position at the outside of the storage chamber and under the action of their springs 14.

By means of two kinds of adjusting members, one of which preferably acts upon the rearward extension 15 of the evacuating arms 5, 6 and which are, for example, pins 24' or the like which can be inserted in apertures 24 of the evacuating carriage, and the other comprising slides 30, the quantity of material to be delivered by the evacuating arms 5, 6, more particularly the mixture ra-

tio of the two types of material, can be adjusted. As shown in Figs. 3 and 4, pins 24', when set in the apertures 24, extend into the path of the extensions 15 and abut the same to limit the degree of operative movement of the arms 5, 6. When less material is to be scraped out through the slits 30' by the arms 5, 6, these are pivoted inwardly to bring their extensions 15 on the outer side of the apertures 24. A pin 24' is then set in one of the three apertures 24. Thus, when the springs 14 act to open arms 5, 6, outwardly, this outward movement is limited by the inward movement of the extensions 15 being limited by the pins set in the apertures 24. With three apertures as shown, there is provided three different degrees of discharge and one degree for no discharge by each of the arms 5, 6. By means of the setting of pins 24' in one of the apertures 24, either one of the two evacuating arms of each pair 5, 6 can be entirely cut out of operation for delivery. A regulation of this type can also be effected by the other kind in the form of slide members 30, since upward and downward adjustment of the slides 30' permit more or less of the material to pass, due to the changes in height of the slit 30', as shown in Fig. 3a.

By means of the infinitely variable transmission 33 of the speed of the evacuating carriage 4, and hence the total quantity of material to be delivered, can be regulated.

I claim:

1. Slit type storage chamber comprising a central saddle member dividing said chamber into compartments for stored material one on either side thereof with a slit 30 between each compartment and the saddle, evacuating arms advanceable along the saddle between the slits of the compartments and movable into and out of the two compartments respectively, each arm being pivotally mounted and having a rearward extension at an angle to the arm, locking hooks located near the rearward extensions of the evacuating arms and maintained under spring tension to maintain the evacuating arms in an inoperative position, means for automatically tripping the locking hooks at the end positions of the slits to release the evacuation arms, and a tension spring normally urging the evacuating arms to operative position.

2. Slit type storage chamber according to claim 1, characterized by diagonal surfaces disposed at the ends of the storage chamber in the path of the rearward extensions of the evacuating arms in their operative position to actuate the rearward extensions to move their evacuating arms out of the operative into the inoperative position and with simultaneous movement of the rearward extension into the locking hooks for latching relation with the locking hooks, and further characterized by the aforesaid tripping means comprising stops disposed outside the storage chamber at the ends of slits in position to abut the locking hooks to release the evacuating arms for pivoting under their spring tension into the operative position.

3. Slit type storage chamber according to claim 1, characterized by adjustable means for extending the lower terminus of the saddle downwardly for regulating the height of the slits and by individually adjustable means for limiting the degree of movement of the evacuating arms through the slits, whereby to vary the quantity of material delivered by the evacuating arms.

4. Slit type storage chamber according to claim 1, characterized by a series of pin recesses in the path of said extensions and abutment members removably insertable in the recesses to vary the extent of movement of the evacuating arms through the slits.

5. Slit type storage chamber according to claim 2, characterized by adjustable slides on the lower terminus of the saddle for decreasing the height of the slit whereby to vary the width of material of the compartments that is exposed to the evacuation arms for evacuation by the arms during their advancement along the saddle.
